UNITED STATES PATENT OFFICE.

ALFRED PIGUET, EWALD STEINBUCH, AND ROBERT STOCKER, OF BASEL, SWITZERLAND, ASSIGNORS TO SOCIETY OF CHEMICAL INDUSTRY IN BASLE, OF BASEL, SWITZERLAND.

PROCESS FOR THE MANUFACTURE OF AROMATIC AMINO-OXY-COMPOUNDS.

1,239,822.

Specification of Letters Patent. Patented Sept. 11, 1917.

Application filed October 27, 1916. Serial No. 128,009.

To all whom it may concern:

Be it known that we, Dr. ALFRED PIGUET, Dr. EWALD STEINBUCH, and Dr. ROBERT STOCKER, all three citizens of the Swiss Republic, and residents of Basel, Switzerland, have invented a new and useful Process for the Manufacture of Aromatic Animo-Oxy-Compounds, of which the following is a full, clear, and exact specification.

- 10 By the electrolytic reduction of an aromatic nitrocompound in an acid electrolyte two principal products are obtained in varying quantities *i. e.* the corresponding amin and the corresponding amino-oxy-compound. For instance the reduction of nitrobenzene in sulfuric acid conduces to anilin and 1-4-amino-oxy-benzene (paraamidophenol) according to the formulæ:
- 15 $C_6H_5NO_2 + 6H = C_6H_5NH_2 + 2H_2O$
- 20 and
- $C_6H_5NO_2 + 4H = C_6H_5NHOH + H_2O \rightarrow C_6H_4NH_2OH + H_2O$.

By using a tin, chromium or lead cathode, or an indifferent cathode in presence in the 25 cathode chamber of tin chromium or lead or of the corresponding metal-compound, Buchner (U. S. A. Patents No. 700670, 736205, 761284) attains a pretty uniform reduction to amin, also in commercial working. On the other hand it has not been possible to reduce on a large scale the nitrocompounds to the corresponding amino-oxycompounds (by the methods hitherto employed).

30 In the manufacture of aromatic amino-oxy-compounds by electrolytic reduction of nitro-compounds in presence of sulfuric acid of various strengths, cathodes of carbon or of a noble metal, such as platinum or silver have been used hitherto. Cathodes of nickel 35 have also been recommended but have not been adopted in commercial working. The use of other common metals appears to be excluded since they conduce to the formation of amino-compounds in preponderating proportion.

In the case of cathodes of a number of common metals, when the surface of the metal is clean, that is to say polished, the 40 production of the amino-compound is diminished in comparison with that of the amino-oxy-compound; but after the cathodes have been in use for some time their surfaces become changed and the formation 45 of the amino-compound continually in-

creases. The attempt might be made to keep the metal surface polished, but this is scarcely practicable. The said change of the cathode surface is due to the fact that, particularly in presence of a nitro-compound, some of the cathode metal dissolves in the electrolyte and in the course of the electrolysis is deposited on the cathode surface in a form which especially favors the formation of amino-compounds. Such deposition, therefore, is intentionally produced by Buchner to carry the reduction nearly completely to amino-compound, by using an indifferent electrode and adding a salt of copper, iron, chromium, lead or mercury, or the corresponding finely subdivided metal to the electrolyte.

We have discovered that, if there are at least two metals present in such a deposit on the cathode, the reduction tends to cease 75 when the amino-oxy-compound has been formed.

By the present invention, therefore, the formation of amino-oxy-compounds is favored by conducting the electrolysis in the 80 presence of two or more metals, which by continuously passing into solution and depositing on the surface of the cathode maintain the latter more or less coated with a deposit of two or more metals. When a cathode of a common metal is used this may supply one of the metals in the manner indicated above; the other may be added either as such or in the form of a salt. When an indifferent cathode is used at least 90 two metals must be added to the electrolyte, each as such or as a salt.

By the present invention the formation of amino-oxy-compounds is consequently favored if two or more suitably selected metals 95 are present at the same time in the cathode chamber. For instance, when nitrobenzene is reduced in dilute sulfuric acid with a lead cathode, para-aminophenol and anilin are produced in the proportion 100:150, and 100 if then in the same apparatus with the same lead cathode there is added to the cathode chamber some powdered bismuth, the anilin content of the product of the next electrolytic reduction falls to about 20 per cent. 105 of the aminophenol. In succeeding operations the proportion is at first approximately the same and then gradually varies unfavorably to the aminophenol because every time the apparatus is emptied there is 110

a loss of bismuth dissolved or suspended in the electrolyte. By adding more bismuth the favorable proportion is again established.

5. The effect of the presence of more than one metal in hindering the formation of amino-compound and favoring that of amino-oxy-compound is not limited to the aforesaid lead-bismuth combination. The 10 cathode may be of any suitable material and the metal or metals adapted for the case in point may be added. Thus we have used a large number of other metals, for instance arsenic, antimony, copper, nickel, tin, mercury and by combining them, as for instance copper with mercury, lead with arsenic, copper with tin and arsenic, so that they deposit on the cathode as required, we have obtained always the same or similar effects. 15 20 If the cathode is an indifferent material, like carbon, the presence of suitable metals, such as copper and lead, has the advantage that no adherent coating of resin is produced on the cathode. As already stated 25 the metals may be added in the form of their salts; for instance when using a lead cathode, copper sulfate may be added.

In the German Patent No. 252759 it has already been proposed that lead containing 30 a small proportion of copper should be used as electrode material, but these electrodes are not suitable for the purpose in question when the working is continuous, apparently because at each successive operation the 35 cathode surface becomes poorer in copper until finally the surface consists merely of lead-sponge, whereupon the reduction is completely to the amino-compound.

The cathode for producton of amino-oxy- 40 compounds may, however, be made of metals alloyed together instead of using one metal as cathode and adding another as an auxiliary, provided that the metals to be alloyed are so selected that even in continuous 45 application of the cathode the proportion between the metals present on the cathode surface is not essentially altered, a condition not existing, as already stated, in the lead-copper alloy previously suggested.

50 Besides the advantage that one is not restricted in the choice of the electrode material, the invention has the further important advantage that there need not be present in the electrolyte in the cathode 55 chamber much more acid than will be combined at the end of the reduction with the base produced, and this limitation of the acid does not affect unfavorably the yield of the amino-oxy-compound. The consumption 60 of acid is therefore the smallest possible, whereas according to former tenets the formation of amino-oxy-compound has been the better, the more concentrated the acid used as electrolyte.

The following examples illustrate the invention, the accompanying drawing showing in a vertical section one of the many forms of apparatus which may be employed:

Example 1: The electrolytic vessel is a 70 lead cylinder 1 which serves as anode. In it is placed a porous cylinder 2 containing a copper cathode 3 in the form of a hollow perforated cylinder. Within the cathode cylinder is a suitable stirrer 4. Into the 75 cathode chamber extend one or more rods of lead 5. The anode chamber is charged with sulfuric acid of 30 per cent. strength, and the cathode chamber with 25 liters of sulfuric acid of 15° Baumé specific gravity 80 and 6 kilos of nitrobenzene. By lively stirring the nitrobenzene is kept in emulsion in the sulfuric acid. The electrolysis is conducted at a temperature of 80-95° C. with a current of about 3 amperes per sq. decm. 85 of cathode surface at 3-3½ volts, until all nitrobenzene has disappeared. The bases are liberated from the mass by adding milk of lime and the anilin formed as a by-product is distilled. The remaining hot solution of para-aminophenol is filtered from calcium sulfate and evaporated to crystallization. There is thus obtained pure para-aminophenol in yield of about 50 per cent. 90 of the weight of the nitrobenzene used, and as by-product anilin in a proportion of about 20 per cent. of the weight of the para-aminophenol simultaneously obtained. If arsenic is present as well as the copper and lead, such as is the case if arsenical sulfuric 100 acid is used as the electrolyte, the content of anilin will fall to 10-15 per cent. of the aminophenol. Instead of the arrangement described the cathode may be of lead and a copper rod may be suspended in the cathode 105 chamber or some copper sulfate may be added to the chamber and renewed from time to time.

Example 2: Instead of the copper cathode described in Example 1, a lead cathode is 110 used and instead of the lead rods there are introduced into the cathode chamber about 20 grams of metallic bismuth. The electrolysis and the working up of the products are conducted as in Example 1. Para-aminophenol is obtained in yield of about 50 per cent. of the weight of the nitro-benzene used and the anilin produced amounts to about 14 per cent. of the weight of the para-aminophenol.

120 What we claim is:

1. The herein described process for the manufacture of amino-oxy-compounds by electrolytic reduction of aromatic nitro-compounds in acid, which consists in conducting the electrolysis in presence of at least two metals in the cathode chamber, which by continuously passing into solution and de-

positing on the surface of the cathode, maintain the latter always coated with a deposit of at least two metals.

2. The herein described process for the manufacture of amino-oxy-compounds by electrolytic reduction of aromatic nitrocompounds in acid, which consists in employing as electrolyte in the cathode chamber a diluted acid solution which contains not much more acid than is necessary to combine with the bases produced by the reduction.

3. The herein described process for the manufacture of amino-oxy-compounds by electrolytic reduction of aromatic nitrocompounds in acid, which consists in employing as electrolyte in the cathode chamber a diluted acid solution which contains not much

more acid than is necessary to combine with the bases produced by the reduction and in 20 conducting the electrolysis in presence of at least two metals in the said cathode chamber, which by continuously passing into solution and depositing on the surface of the cathode, maintain the latter always coated 25 with a deposit of at least two metals.

In witness whereof we have hereunto signed our names this 6th day of October 1916, in the presence of two subscribing witnesses.

DR. ALFRED PIGUET.
DR. EWALD STEINBUCH.
DR. ROBERT STOCKER.
